UNITED STATES PATENT OFFICE.

THEA FINSTAD, OF MINNEAPOLIS, MINNESOTA.

MOP PAIL WITH WRINGING ATTACHMENT.

Application filed August 16, 1928. Serial No. 299,991.

My invention provides an improved mop pail with a wringing device of novel design and arrangement applied thereto and, generally stated, the invention consists of the 5 novel devices, combinations of devices and arrangement of parts hereinafter described and defined in the claims.

The wringing device employed in this improved pail differs radically from the ordinary wringers employing rollers or co-operating squeezing devices and it is in the nature of a perforated funnel-shaped or downwardly tapered conical squeezing chamber into which a mop is adapted to be pressed 10 and then wrung by downward pressure and rotation of the mop within said squeezing chamber.

A commercial form of the invention is illustrated in the accompanying drawings, 20 wherein like characters indicate like parts throughout the several views.

Referring to the drawings:

Fig. 1 is a plan view of the improved pail with the wringing device applied thereto:

Fig. 2 is a vertical section taken on the line 2—2 of Fig. 1; and

Fig. 3 is an enlarged fragmentary section taken on the line 3—3 of Fig. 2.

The pail 4 which is preferably of galvanized iron structure is made oblong and a transverse rod 5 is passed about centrally through the upper rim portion thereof and is formed with upturned eyes 6 at its outer ends, to which a carrying bail 7 is attached. 30 That portion of the pail that is at one side of the rod 5 is left open, but the other side thereof is covered by a sheet metal plate 8 that is attached to the rim of the pail and to the transverse rod 5 and is formed with a 35 deep depending funnel-shaped or downwardly tapered conical portion 9 that affords the mop-squeezing chamber of the wringing device.

The bottom of this chamber 9 is provided 45 with a plurality of perforations 10 and the downwardly converging side walls thereof are formed with long slots 11. The metal cut loose to form the slots 11 is bent inward to form approximately cylindrical 50 beads 12 that project into the squeezing chamber and afford cleats or ribs that catch and hold the mop against rotation when the

latter is pressed downward and rotated within said squeezing chamber.

The suds or soapy water *y* contained with- 55 in the pail should be kept below the perforated bottom of the squeezing chamber 9 so that any water squeezed from the mop will run freely back into the pail.

This pail and its wringing attachment 60 are adapted for use in connection with mops of various form, but such mops should not have wide heads that will interfere with the downward pressing and twisting movements 65 of the mop within the squeezing chamber. 65

In scrubbing floors, the mop can be freely inserted into the suds through the open side of the top of the pail. To wring the mop, it will be dropped down into the funnel-shaped squeezing chamber 9 and then downwardly pressed and twisted or rotated. The 70 rotation of that portion of the mop that contacts with the walls of the conical chamber 9 will be held against rotary movement by friction and by the action of the ribs 12 75 and hence the mop thus pressed downward and twisted will be turned into very compact arrangement and the surplus water will be squeezed therefrom and will run from the squeezing chamber out through the slots 11 80 and through the bottom perforations 10. The mop-wringing action above described 85 may be very quickly and easily accomplished and does not require any of the different pressing and pulling actions required in the use of wringers of the roller type and may be easily performed by a woman or child. Moreover, the device is simple and of comparatively low cost as well as extremely high 90 efficiency.

What I claim is:

1. A mop pail having a substantially elliptical open top, a rod in the minor axis of the elliptical top and terminating substantially at the rim, a bail attached to the ends of said rod, a metal plate anchored to said cross rod and to approximately one-half of the rim of said pail and provided with a downwardly tapered funnel-shaped mop-squeezing chamber, formed with openings for the 100 escape of water from the mop.

2. A mop pail having a substantially elliptical open top, a rod in the minor axis of the elliptical top and terminating sub-

stantially at the rim, a bail attached to the ends of said rod, a metal plate anchored to said cross rod and to approximately one-half of the rim of said pail and provided with a downwardly tapered funnel-shaped mop-squeezing chamber, the bottom of said pail having perforations and the side walls

of said squeezing chamber being formed with upright slots and with an inturned rolled rib-forming portion at each upright ¹⁰ edge of each of said slots.

In testimony whereof I affix my signature.

THEA FINSTAD.
